UNITED STATES PATENT OFFICE.

EDSON B. WILCOX, OF MERIDEN, CONNECTICUT.

ELECTRICAL FITTING.

No. 898,540.

Specification of Letters Patent.

Patented Sept. 15, 1908.

Application filed May 29, 1908. Serial No. 435,736.

To all whom it may concern:

Be it known that I, EDSON B. WILCOX, a citizen of the United States, residing at Meriden, in the county of New Haven and State of Connecticut, have invented certain new and useful Improvements in Electrical Fittings, of which the following is a specification.

My invention relates to improvements in electric fittings.

10 I have illustrated it as embodied in a rosette or connection box.

It has been customary to tie a knot in the conducting cord inside a rosette so as to dispense with any stress upon the terminals.

15 This is likely to cause a short circuit and sometimes the knot pulls through. It has also been proposed to twist the conductor or conductors about some projection on the exterior of the rosette or to pass the conductors

20 through tortuous passages. These devices are either expensive to manufacture or else difficult to install.

It is my object to construct a simple, cheap device and which can be readily installed without danger of injury to the conductors.

25 Figure 1, is a vertical section of a fitting embodying my invention attached to a ceiling block. Fig. 2, is a plan view of the fitting. Fig. 3, is a bottom view. Fig. 4, is a section on the plane of the line X—X Fig. 3. Fig. 5, is a section on the plane of the line Y—Y Fig. 3.

30 The block 1, is secured to the ceiling 2, in any suitable manner. The main circuit terminals 3 and 4 are suitably secured to block 1.

35 The rosette body 5, is preferably made of porcelain in one piece and is removably secured to the ceiling block by the terminals 6 and 7. The flange or wall 8 forms an interior chamber sufficiently large to accommodate the wires, screws etc. The terminals 6 and 7 are secured on the floor 9 of this chamber and extend through notches 10 and 11 in the wall or flange 8.

40 The body is formed with a number of intersecting straight channels and passages for receiving the conducting wires. From the central passage 12 branches the small interior channel 13 which meets the passage 14. The exterior channel 15 extends from passage 14 to passage 16. Channel 17, passage 18, channel 19 and passage 20 correspond with channel 13, passage 14, channel 15 and

55 passage 16 on the opposite side. These passages and channels are of such a nature that they may be readily formed in the ordinary process of casting or molding. The wires 21 and 22 which are customarily insulated are drawn through the passages just described, 60 respectively.

65 The spacing and dimensions are such as to give the most effective hold upon the conductors. For instance, the thin wall 23 formed between the passages 12 and 18 causes the wire 22 to take an abrupt but not sharp angle. The wire once bent into this angle holds securely. The wall 24 gives a good frictional surface for the insulation so that it affords additional resistance. The 70 wires 21 and 22 are secured to the terminals 6 and 7 respectively. This is much preferable to the use of separate terminals since it absolutely prevents mistakes in connecting up the wires and insures uniformity in 75 arrangement.

I prefer to form a rather long neck or collar 25 on the body so as to prolong the central passage 12. This prevents displacement 80 of the wires and protects them. It also acts as a sort of guard to the parts of the conductors located in the exposed channels 15 and 19.

85 The proportions shown are preferred but I wish it understood that each claim is limited only by its own terms and as set forth in the specification.

90 Obviously any device may be suspended from the wire 21 and 22, for instance a lamp. So also it is obvious that the fitting may itself be inverted and supported by the wires. The design of the fitting will be modified to suit the particular requirements of its use. The shape of the terminals is also unimportant and will depend upon the circumstances 95 of individual cases.

What I claim is:—

1. An electrical fitting comprising an integral body of insulating material and having a flange forming an interior chamber, terminals 100 secured to the body within said chamber, said body also having a main vertical passage, two pairs of vertical passages and two exterior channels, each channel connecting the outer ends of the passages of one of the 105 pairs of passages.

2. An electrical fitting comprising an integral body having a lateral flange and a cen-

tral collar, a pair of terminals secured to the body within the flange, said body and collar having a passage for wires, and two pairs of eccentric passages one for each of two wires.

5 3. An electrical fitting comprising an integral body having a central passage and two pairs of lateral passages with internal and external connecting channels and two termi-

nals rigidly secured to the body in a fixed position relative to said passages for the purpose 10 specified.

EDSON B. WILCOX.
